UNITED STATES PATENT OFFICE.

EGBERT H. GOLD, OF CHICAGO, ILLINOIS.

VALVE.

No. 925,692.

Specification of Letters Patent.

Patented June 22, 1909.

Application filed February 2, 1909. Serial No. 475,610.

To all whom it may concern:

Be it known that I, EGBERT H. GOLD, a citizen of the United States, residing at Chicago, in the county of Cook and State of Illinois, have invented certain new and useful Improvements in Valves, of which the following is a specification.

My invention relates to a valve, and more particularly to a valve for controlling simultaneously the supply and return conduit of a fluid circulatory system, whereby the fluid may be either sent through a long circuit or short circuited, as may be desired.

The object of the invention is to provide a simple, economical and durable valve of this character.

One of the principal objects of the invention, to be more particular, is to provide the valve casing of a device of this sort with an additional port, other than the long circuiting and short circuiting ports, and to construct the valve piece so that it closes this port when in its long circuiting position, and when in its short circuiting position opens and puts this port into communication with the part of the circulatory system cut out.

The invention has for other objects, such new and improved constructions in valves, and particularly in short circuiting valves as will be described in the following specification and particularly set forth in the claims appended thereto.

The valve of my invention may be used in a heating system to control the flow of heating medium, or in other connections.

The invention, in a typical embodiment, is illustrated in the accompanying drawings, wherein—

Figure 1 is a sectional plan of the valve device taken on line 1—1 of Fig. 2. Fig. 2 is a vertical sectional view on line 2—2 of Fig. 1, looking in the direction of the arrows. Fig. 3 is a detail view in perspective of the valve piece, and Fig. 4 a sectional plan on line 4—4 of Fig. 2.

Like characters of reference indicate like parts in the several figures of the drawings.

Referring to the drawings, 10 represents the valve casing, provided with the pair of short circuiting ports 11 and 12 in one side and the pair of long circuiting ports 13 and 14 in the opposite side. These ports are screw-threaded, preferably. A supply pipe 15 connects with the casing at port 11, and a return pipe 16 leads from port 12.

17 and 18 respectively, represent the supply and return pipes of the part of the circulatory system, designed to be cut out when occasion shall demand. For convenience, the 60 casing is provided with two openings corresponding, to ports 11 and 12, through the side of the casing adjacent the side having the ports 11 and 12 such openings being closed by plugs 19 and 20 when ports 11 and 12 are 65 used. The interior of the casing is constructed with the webs 24, 25, 26 and 27, which constitute seats for the rotary valve piece. Through the bottom of the casing on the long circuiting side, that is, the side 70 nearest ports 13 and 14, is an additional port 21, which when the valve is used with a steam heating system, serves as a drip port to drain the radiating pipes when they are cut off from the supply and return pipes. 75 The lower side of the casing is, preferably, constructed with the integral boss 22 which surrounds port 21 and into which may be fitted the drip pipe 23.

The valve piece, shown in detail in Fig. 80 3, consists of the lower disk 28, the upper disk 29, and the connecting web 30. Disk 29 has the perforation 31 which registers with perforation 21 when the web 30 stands across the space between webs 25 and 27. 85 The upper disk has one or more perforations 32. On the upper disk is the squared projection 33, and also the lug 34 which extends out a trifle beyond the edge of the disk. The valve piece sets into the space between webs 90 24, 25, 26 and 27, resting on the bottom of the casing. On the upper side of the casing is, preferably, the integral boss 35, the interior of which is recessed for a part of its circumference as shown at 36 into which recess extends the lug 34, the shoulders 37 and 38 made by this recess forming stops to limit the rotation of the valve piece to a quarter turn. Into the boss 35 is threaded a cap piece 39, the boss 35 and the cap piece 100 constituting a pressure chamber 40, above the upper disk of the valve piece, which is in communication with the interior of the casing through ports 32. Preferably, a spring 41 is placed between the cap piece 39 and 105 the upper disk of the valve piece. The valve piece is manipulated by handle 42 attached to a stem 43 which extends through the boss 44 on the cap piece 39 and is provided with a socket 45, extending over the squared projection 33 on disk 29. The continuation 46 of boss 44 overhangs the upper side of socket 110

45, so that the valve piece and its stem are kept in engagement. Packing 47 for the stem 43 may be provided in a stuffing box formed by the cap nut 48 which screws on 5 to boss 44.

I do not limit myself to the exact constructions shown and described as modifications might be devised which would come within my invention as defined by the claims.

10 The operation of the valve thus constructed is as follows: Supposing for purposes of illustration that it is to be used in a heating system for the purpose of short circuiting the heating medium and cutting out a portion 15 of the circulatory system: With the valve piece turned so that the web 30 comes into the dotted line position, (Fig. 1), the steam will enter the casing through pipe 15 and will pass out to the radiating pipes, for 20 example, through pipe 17. The discharge of steam or water of condensation will be through pipes 18 and 16, which with this 25 position of the valve piece are in communication with each other. The drip port 21 will be closed by the disk 28 when the valve piece is in this position. When it is desired 30 to short circuit the part of the system represented by pipes 17 and 18, handle 42 will be given a quarter turn, bringing the web 30 into the position shown in the full lines (Figs. 1 and 2), ports 11 and 12 will now 35 be in communication with each other so that the heating fluid entering by pipe 15 will leave the casing through pipe 16. Ports 13 and 14 are cut off from ports 11 and 12, but 40 are in communication with each other and are in communication with drip port 21 with which opening 31 in the lower disk 28 will register when the valve piece is in this, 45 its short circuiting position. Therefore, the part of the circulatory system which has been cut out is free to drain out through drip pipe 23.

In order to keep the valve piece down 45 tight against the bottom of the casing and so prevent the escape of steam through the drip port, the valve is so constructed as to introduce pressure above the upper disk of the valve piece. The spring 41 may also be 50 employed with this end in view or as it is of an auxiliary character, it may be omitted.

I claim:

1. The combination with a valve casing having five ports, of a valve piece which puts 55 four of said ports into communication with each other in pairs, and which in one position opens the fifth port, and in another position closes the same.

2. The combination with a valve casing 60 having five ports, of a valve piece which puts each of four of said ports into communication with one or another of two of said four ports in accordance with the position of said valve piece, and which in one of said

positions closes, and in the other opens the 65 fifth port.

3. The combination with a valve casing having five ports, of a valve piece which puts each of four of said ports into communication with one or another of two of said 70 four ports in accordance with the position of said valve pieces, and which in one of said positions closes the fifth port, and in the other position puts the same in communication with one pair of said first named communicating ports, while shutting off communication between said fifth port and the other pair of communicating ports.

4. The combination with a valve casing having two short circuiting ports, two long 80 circuiting ports and a fifth port, of a valve piece, which according to its position puts into communication either, each of the short circuiting ports with one of the long circuiting ports, or the two short circuiting ports 85 with each other and the two long circuiting ports with each other and with said fifth port.

5. The combination with a valve casing having two short circuiting ports, two long 90 circuiting ports and a fifth port, of a valve piece, which according to its position puts into communication either each of the short circuiting ports with one of the long circuiting ports, or the two short circuiting ports 95 with each other and the two long circuiting ports with each other and with said fifth port, said valve piece closing said fifth port when in its first named position.

6. The combination with a valve casing, 100 having two pairs of adjacent ports, said pairs being arranged on different sides of said casing, and a fifth port through the bottom of said casing; of a rotating valve piece, which according to its position puts into 105 communication, either the ports of one pair with the ports of the other pair, or adjacent ports of each pair with each other and one of said pairs with the fifth port, said valve piece arranged so as to close said fifth port 110 when in its first named position.

7. The combination with a valve casing having two short circuiting ports, two long circuiting ports and a fifth port, of two pairs 115 of valve seats in said casing, a rotary valve piece adapted to co-act with one or another of said pairs of seats, so as either to put each of said short circuiting ports in communication with one of the long circuiting ports, or to put the short circuiting ports in communication with each other and the long circuiting ports in communication with each other, and means on said valve piece for opening and closing said fifth port, according to the position of said valve piece.

8. The combination with a valve casing having two short circuiting ports, two long circuiting ports and a fifth port, of two pairs

- of valve seats in said casing, a rotary valve piece adapted to co-act with one or another of said pairs of seats, so as either to put the short circuiting ports in communication with each other and shut off the long circuiting ports therefrom, or shut off the short circuiting ports from each other and put each of the same into communication with one of the long circuiting ports, and a disk on said valve piece which closes said fifth port when the valve piece is in its first named position, said disk provided with a perforation which registers with said fifth port when the valve piece is in its short circuiting position.
9. The combination with a valve casing having a pair of short circuiting ports, and a pair of long circuiting ports in the sides thereof, and having a drip port through the bottom thereof, on the long circuiting side of said casing; of a rotating valve piece comprising a pair of disks, and a connecting web, and valve seats in said case between the ports with which said web co-acts, said lower disk being provided with a perforation which registers with said drip port when the valve piece is in its short circuiting position.
10. The combination with a valve casing having a pair of short circuiting ports, and a pair of long circuiting ports in the sides thereof, and having a drip port through the bottom thereof, on the long circuiting side of said casing; of a rotating valve piece comprising a pair of disks, and a connecting web, and valve seats in said case between the ports with which said web co-acts, said lower disk being provided with a perforation which registers with said drip port when the valve piece is in its short circuiting position.
11. The combination with a valve casing having a pair of short circuiting ports, and a pair of long circuiting ports in the sides thereof, and having a drip port through the bottom thereof, on the long circuiting side of said casing; of a rotating valve piece comprising a pair of disks, and a connecting web, and valve seats in said case between the ports with which said web co-acts, said lower disk being provided with a perforation which registers with said drip port when the valve piece is in its short circuiting position, the upper disk being provided with a perforation, the casing above said disk being so constructed as to form a pressure chamber above said disk, and a spring which bears against the upper disk.
12. The combination with a valve casing, provided with two pairs of ports formed in different sides of the casing, and a fifth port through the bottom of said casing, of webs on the inside of said casing, located one between each of said first named four ports, a rotary valve piece in the space between said webs, said valve piece consisting of an upper disk, and a lower disk, the lower disk being provided with a perforation which registers with said fifth port when the valve piece is in one position, said upper disk being provided with a perforation, a boss on the upper side of said casing, a cap piece engaging the said boss and forming therewith a pressure chamber above the valve piece, a stem having an operating handle to operate said valve, a squared projection on the top of said valve piece and a socket on said stem which engages said squared projection.
